UNITED STATES PATENT OFFICE.

FRANK BILLINGS AND ROBERT P. GREENLEAF, OF CLEVELAND, OHIO; SAID GREENLEAF ASSIGNOR TO SAID BILLINGS.

LOADING MACHINE.

Application filed July 23, 1919. Serial No. 313,947.

To all whom it may concern:

Be it known that we, FRANK BILLINGS and ROBERT P. GREENLEAF, citizens of the United States, and residents, respectively, 5 of Cleveland, in the county of Cuyahoga and State of Ohio, and Cleveland, in the county of Cuyahoga and State of Ohio, have invented a certain new and useful Improvement 10 in Loading Machines, of which the following is a full, clear, and exact description.

This invention relates to loading machines of what may be termed the hoe type, such as illustrated in patents granted to Frank Billings, one of the co-inventors herewith, Nos. 1,095,786, 1,265,729, and 1,265,730, and in a 15 patent granted jointly to us No. 1,277,687, machines of this type including a conveyor suitably supported by a truck or wheeled 20 frame and a hoe carried by a ram or hoe support mounted for forward or rearward reciprocating movement, and for swinging movements vertically and laterally so that the hoe can be actuated to reach material at 25 the front or at the sides of the machine and scrape the same rearwardly up an inclined apron at the front of the conveyor frame to the conveyor, or a suitable open bottom hopper positioned over the forward end of the 30 conveyor.

The principal object of this invention is to improve the efficiency, and at the same time to provide a much simplified machine especially by reducing the number of actuating parts required to give the hoe the desired movements.

The present improvements relate in one aspect of the invention to the construction 40 of an apron at the front of the conveyor frame, the apron in accordance with our present invention being stationarily mounted with respect to the lateral movements of the hoe, but so constructed that material may be scraped up along the same to the conveyor or receiving hopper, irrespective of the angle that the arm makes with respect to the central longitudinal axis of the machine.

In another aspect the invention relates to 50 certain improvements in the actuating mechanism for the hoe and ram, including certain guides which control the path of movement of the hoe as it is retracted, and which cause the ram on its outward stroke to be elevated without requiring a special

motor for imparting the vertical swinging or elevating movement.

The invention may be further briefly summarized as consisting in certain novel details of construction and in certain combinations and arrangements of parts which will be described in the specification and set forth in the appended claims.

In the accompanying sheets of drawings, wherein we have shown one embodiment of our invention which operates with high efficiency, Fig. 1 is a side view of the machine, with the ram extended and ready to be lowered to sink the hoe into the material to be scraped up onto the conveyor; Fig. 2 is a view looking at the opposite side of the machine, with the ram wholly retracted, certain removable portions of the sectional conical apron at the front of the machine being removed; Fig. 3 is a top plan view of the same with the parts in the positions shown in Fig. 2; Fig. 4 is a sectional view substantially along the irregular line 4—4 of Fig. 2; Fig. 5 is a front view of the machine; Fig. 6 is a detail sectional view taken through the outer ram member substantially along the line 6—6 of Fig. 1; Fig. 7 is a view similar to Fig. 2, showing the ram extended and partially lowered to the position shown by full lines in Fig. 1; and Fig. 8 is a horizontal section through the brake cylinder and controlling valve.

The machine includes a suitable wheeled frame or truck 10 designed to run along a track which may be a track in a mine, since this machine is adapted especially for use

as a loading machine in mines to load loosened material such as coal and ore into mine cars. On the truck or wheeled frame 90 10 is supported a superstructure including a conveyor frame 11, carrying a suitable endless conveyor 12, which extends from the lower front part of the machine upwardly and rearwardly to a height such that mine cars or other receiving elements may be run

underneath the discharge end of the conveyor. The conveyor and the frame may be constructed in any suitable manner, as the invention does not reside directly in these parts, and the conveyor may be operated in any suitable manner such as by a motor 13, shown in Fig. 2, suitably connected by gearing and chain and sprocket driving mechanism which need not be described in detail,

90

105

to one of the drums about which the endless conveyor travels.

The frame 11 of the superstructure has a forward extension 14 above the front end 5 of the conveyor, and on this extension there is pivoted by means of a suitable king bolt or equivalent device 15 (see Fig. 4) a turntable 16. This turntable which may be supported by rollers in addition to the king pin 10 so that it may swing or turn from its center position about 90° in either direction, carries a housing 17 having hollow trunnions 18, which extend laterally outward into, and are journaled in bearings 19 of the turntable. 15 This mounting of the housing it will be understood, enables the housing to swing vertically. Mounted to reciprocate in this housing is a two-part telescopic ram such as shown in some of the prior patents heretofore mentioned, this ram being composed of 20 an outer or primary part 20, and an inner or secondary part 21, the former being mounted directly in the housing and the latter being carried by the former or primary part and adapted to travel inwardly and outwardly at twice the speed of the latter. To the forward end of the secondary or inner part of the ram is adapted to be secured 25 a hoe 22, which scrapes the material up to the conveyor.

The outer or primary part of the ram is as shown in Fig. 4, a box-like structure of rectangular shape supported from the housing by rollers 23, and by a shrouded pinion 35 24, the latter being mounted on a motor driven shaft 25, which in this instance is rotatably mounted in the hollow trunnions of the housing 17, and adapted to be actuated by any suitable reversing motor 26 carried by 40 the turntable. In this instance the motor is connected by a worm and worm wheel gearing 27, shown in Fig. 4, to the shaft 25. The shrouded pinion 24 assists in supporting the primary part of the ram, and it reciprocates 45 it forwardly and rearwardly through the medium of a rack 28 extending lengthwise of and carried by the ram member 20. The secondary or inner member of the ram is supported from the outer or primary member 50 by rollers 29, and by a shrouded pinion 30, carried by the ram member 20. The inner ram member is driven at twice the speed of the outer member by this shrouded pinion 30 which engages a rack 31 (see Fig. 55 4) carried by the inner ram member, and also engages a stationary rack 32 carried by a forward extension 33 of the housing 17. As the details of construction of the ram are not material to the present invention, and as 60 the manner in which the two parts of the ram are actuated one from the other, is substantially like that disclosed in some of our prior patents before mentioned, further description of the construction and operation 65 is deemed to be unnecessary.

Coming now to a part in which the invention is more directly involved, we provide novel devices for controlling the path of the hoe as it is moved inward and outward, as well as for elevating the hoe and ram as they 70 are moved outward without requiring an elevating or vertically swinging motor utilized in the constructions shown in all the prior patents heretofore mentioned. To control the digging depth and the path of the hoe 75 as the ram is retracted, we provide on the outer ram member 20, a guide or cam 34, which is shown by dotted lines in Fig. 1, since this guide is on the far side of the ram member as the same is viewed in this figure. 80 When the ram is being retracted, the lower face of the guide is engaged by a roller 35, which is carried by the turntable, the guide and roller being so positioned that the guide travels over the roller on the retraction of 85 the ram, and the lower face of this guide being so shaped that the point of the hoe is required to travel in a substantially straight horizontal plane. As will be seen by Fig. 2, the roller 35 is journaled in a member 36, 90 pivoted at 37 on the turntable, the roller supporting member 36 resting on the top of an adjusting screw 38 (see Figs. 2 and 6), by which the height or position of the roller with respect to the turntable can be varied 95 to change the height of the plane through which the digging edge of the hoe travels. When the hoe reaches the inclined apron at the front of the machine, which apron will be described presently, the guide leaves the 100 roller and the point of the hoe then rides diagonally upward on the face of the apron.

For elevating the hoe and the ram when the ram is extended or moved outward, we provide guide and roller devices which 105 elevate the ram and the hoe for a portion of the outward movement, and in addition we provide a form of clutch or brake which acts on the housing so as to constrain the ram to move outward at a given inclination for the 110 remainder of the outward movement, and at the same time enables the ram to be dropped at any desired point in the outward movement. To this end we provide on the outer ram member 20, on the near side thereof as 115 the same is viewed in Fig. 1, a guide or cam 39, which co-operates with a roller 40, likewise supported by the turntable. As will be seen by Fig. 6, this roller is carried by a horizontal stud 41 slidably mounted axially 120 in a housing 42 containing a spring 43, which tends to press the roller inward, i. e., toward the face of the cam member 39.

The cam or guide 39 has a lower cam face which is designed to run over this roller, 125 and at its rear end it has a cam face or taper designated 39a. The parts are so disposed that on the retraction of the ram, with the ram inclined downwardly, the beveled face 39a of the cam member 39 engages the 130

side of the roller 40 pressing it outward and so that the side face of the cam member may slide past the roller for a distance. Then when the ram reaches about the inner limit of its movement the face of the roller rides off the face of the cam member, and by the action of the spring 43 the roller is snapped under the lower edge or face of the cam member, the latter being so shaped that as the ram starts on its outward movement this cam member elevates the ram, causing the point of the hoe to travel diagonally upward as indicated by the dotted line A—B. When the hoe reaches the point B, the cam member rides off the roller, but nevertheless the hoe continues outward and upward at substantially the same inclination as while traveling in the path A—B, this being caused by the provision of what was heretofore termed the brake member acting on the mounting. This brake member is in the form of a fluid cylinder 44, adapted to be provided with a quantity of liquid such as oil. This cylinder is pivotally mounted on the turntable at 45, as shown in Fig. 2, and it contains a piston 44^a pivotally connected to the housing at 46. At the side of this cylinder is a by-pass chamber 47 having a valve 47^a adapted to be manually shifted by the operator by a handle 48. As shown in Fig. 8, the construction is such that if the by-pass valve 47^a is in a position such as to prevent passage of liquid from one side of the piston to the other, when the cam member 39 leaves the roller 40, the housing is held against rocking movement and the ram continues outward at the inclination imparted to it by the cam member 39 but when the valve 47^a in the by-pass passageway is shifted so as to permit the by-passing of liquid the braking or holding action of the liquid in the cylinder is stopped and the ram is free to drop so that the hoe will be sunk into the material to be moved rearwardly or toward the machine on the retraction of the hoe. It will be obvious that the operator can swing the lever or handle 48 to shift the by-pass valve so as to cause the ram and hoe to drop in the manner just stated at any point after the cam member 39 leaves the roller 40, it being thus possible for the operator to cause the ram to have any desired outward stroke and to lower the hoe at any point by stopping the motor 26 and shifting the by-pass valve either simultaneously or successively.

In addition to the reciprocating and vertical swinging movements which are imparted to the ram and hoe, provision is made for turning the turntable about the axis of the king pin so as to swing the ram and hoe laterally in order that the hoe may reach and scrape up to the conveyor material located at the sides as well as directly in front of the machine, as is customary in machines of this kind. This movement may be imparted in any suitable manner, but in this instance the motor 13 is utilized for this purpose. It will be seen by reference to Fig. 1, that there is provided at one side 70 of the conveyor frame a vertical shaft 49, provided at the top with a sheave 50, which when rotated in one direction or the other, turns the turntable through the medium of a cable indicated at 51 in Fig. 3, which cable 75 passes around this sheave, around guide sheaves 52, shown by dotted lines in Fig. 3, and around the flanged periphery of the turntable. The shaft 49 may be rotated in either direction by one or the other of a pair 80 of bevel gears 53 which may be individually clutched to the shaft 49 by suitable clutch controlling mechanism, not shown, and adapted to be shifted by the operator while he is stationed on the machine. These bevel gears are designed to be driven in opposite direction by a bevel gear, not shown, on a shaft 54 (see Fig. 2) which is geared to the motor and which drives the conveyor frame 85 as already explained. 90

It was before stated that the hoe scrapes the material up along an inclined apron at the front end of the machine, and it is in the novel construction of the apron that an important part of our present invention resides. 95

Heretofore it has been customary, or at least proposed, to employ an apron in the form of a pan or trough which projects in fixed position downwardly and forwardly 100 at the front end of the machine. This is shown in the three Billings patents previously referred to. In using an apron of this kind it is necessary when the hoe is reaching material at the sides of the machine 105 to bring the material laterally inward in line with the apron by a combined backward and lateral swinging movement of the ram and hoe before the material can be scraped up the apron to the conveyor. 110

It has been proposed also to employ an apron mounted so that it may swing laterally with the ram so as to always be in position to receive the material without swinging the ram back to the center of the machine, irrespective of the angle that the ram makes with respect to the center line 115 of the machine while it is being retracted.

In accordance with our present invention we provide a fixed apron which is so constructed or formed that the hoe can scrape material up the same to the conveyor or hopper irrespective of the position of the ram in its entire range of lateral swinging movement which in this instance is about 120 180°, or 90° in either direction from the central longitudinal axis of the machine. This apron designated as a whole by the reference character 55, is conical, or rather frusto-conical in shape, and when in position 125 130

for use, extends for more than 180° around the front end of the machine, this apron at all points from one rear side edge to the other inclining upwardly from a plane near the ground, so that irrespective of the position of the ram while the hoe is scraping material rearwardly, whether the ram is in front of the machine, or at any point between its central forward position and a position at right angles to the axis of the machine, the hoe may scrape the material directly up the apron whose upper edge is contiguous to the upper edge of a stationary frustro-conical hopper 56 (dish-shaped or concave to an extent co-extensive with the apron 55), this hopper being in a fixed position above the lower end of the conveyor, and being preferably shaped substantially like the hopper 41 of our prior Patent No. 1,277,687, previously referred to.

The apron extending about the front part of the machine, as shown in Fig. 3, if formed in one part would seriously interfere with the movements of the machine, especially when conveyed through mine tunnels, and we therefore form the apron in three sections including a fixed section 55^a, directly in front of the machine, and two removable sections 55^b, 55^b, at the sides of the fixed section and constituting the portions which project laterally out from the front side portions of the machine. All three sections have warped upper or working surfaces forming portions of a conical surface when the parts are assembled.

The fixed and removable parts of the apron are preferably divided along parallel lines, indicated at 55^c, the distance between which being in this instance somewhat less than the over-all width of the machine.

It is immaterial to our invention as to how the fixed and removable portions of the apron are connected together, but we prefer that the fixed portion be provided along its side edges with socketed attaching plates shown at 55^d in Fig. 2, (the removable section 55^b not being shown in this figure), these plates having sockets designed to receive pins on the inner edges of the removable sections of the apron, and further we prefer that the sides of the machine be provided with notches or apron hooks 55^e Fig. 4 adapted to receive pins 55^f at the upper ends of vertical wings 55^g with which the rear ends of the removable sections 55^b of the apron are provided. With this construction the removable portions of the apron can be readily lifted from place when the machine is to be moved from one point to the other, and they can be as easily restored to working position so as to constitute continuations of the central fixed part of the apron.

It will be obvious that our invention both as to the ram controlling and actuating

mechanism, and as to the construction of the apron may be embodied in different forms than here shown, and we therefore do not desire to be confined to the exact arrangements or details herein illustrated.

Having described our invention, we claim:

1. In a loading machine, a ram having a hoe, a support for the ram on which the ram is mounted for movement vertically and backward and forward, a motor for actuating the ram, and means for controlling the path of movement of the hoe as the ram is retracted, comprising a guide rail carried by the ram and a guide roller carried by the ram support.

2. In a loading machine, a ram having a hoe, a support on which the ram is mounted for movement forward and rearward and vertically, a motor for actuating the ram, and means for controlling the path of movement of the hoe as the ram is retracted, comprising a guide rail carried by the ram and a guide roller carried by the ram support, said roller being mounted for adjustment vertically to vary the height of the path of movement of the hoe.

3. In a loading machine such as described, a telescopic ram composed of a primary member and a secondary member adapted to be actuated by the primary member as the latter is moved, a support for the ram on which the ram is mounted for reciprocating movements and for swinging movements vertically, a motor connected to the primary member of the ram for actuating the same, a guide rail carried by the primary member of the ram, and a roller carried by the ram support over which the guide rail is adapted to travel.

4. In a loading machine of the character described, a ram support, a member mounted on said support for rocking movement vertically, a ram mounted for reciprocating movement in said member, a motor for reciprocating the ram, and means comprising a brake device connected to said member and support for holding the ram at a fixed inclination as it is moved outwardly.

5. In a loading machine of the character described, a ram support, a ram adapted to be provided with a scraping hoe, a housing carried by the ram support and receiving the ram, said housing being mounted for swinging movement vertically, and the ram being mounted in the housing for reciprocating movement, a motor operatively connected to the ram to reciprocate the same, and means comprising a brake connected to the housing for holding the same against movement while the ram is traveling through a portion of its movement, and for allowing the ram to drop so that the hoe may sink into the material to be handled.

6. In a machine of the character described, a support, a housing mounted on the support for swinging movements vertically, a ram carried by the housing and 5 mounted for reciprocating movement relative thereto, a motor for reciprocating the ram, means for swinging the ram vertically and for holding the same at a fixed inclination as it is moved outwardly, and means 10 under the control of the operator for permitting the ram to drop at any desired point in its outward movement.

7. In a machine of the character described, a support, a housing mounted on the 15 support for rocking movement vertically, a ram mounted in the housing for reciprocating movement and adapted to be provided with a scraping hoe, a motor connected to the ram for reciprocating the same, means 20 for causing the ram to be elevated at the start of its outward movement, and a brake connected to the housing for constraining the ram against swinging movement until the hoe reaches a predetermined point selected by the operator.

8. In a machine of the character described, a support, a housing mounted on the support for rocking movement vertically, a ram carried by the housing for reciprocating movement relative thereto, a motor connected to the ram for reciprocating the same, and means comprising a hydraulic brake connected to the housing and to a fixed part and controllable by the operator to hold 35 the ram elevated as it is moved outward, and for permitting the ram to be lowered when the hoe reaches a predetermined or desired position.

9. In a machine of the character described, a support, a ram mounted thereon for reciprocating movement and for swinging movement vertically, a motor connected to the ram for reciprocating the same, co-operating guide members for causing the 45 ram to be elevated as it is moved outward, and additional means for holding the ram elevated independently of said guide members.

10. In a machine of the character described, a support, a ram carried thereby and mounted for reciprocating movement and for swinging movement vertically, a motor connected to the ram for reciprocating the same, co-operating guide members, 55 one carried by the ram, for elevating the ram as it is moved through a portion of its

outward stroke, and means comprising a hydraulic brake for holding the ram elevated for the remainder of the outward movement of the ram, and for permitting 60 the ram to be lowered when the hoe reaches a predetermined outward position.

11. In a machine of the character described, a frame having a conveyor, a ram mounted on the frame for reciprocating 65 movements and for swinging movements including a lateral movement to either side of the machine, a material scraping hoe carried by the ram, and a frustro-conical apron extending about the front of the machine 70 so that the hoe may scrape material up the same to the conveyor irrespective of the angle that the ram makes with the center line of the machine when the ram is retracted.

12. In a loading machine, a frame having a material receiving hopper at the lower front portion thereof, a frustro-conical apron extending about the front of the machine around the upper edge of the hopper, in combination with a hoe, and a hoe 80 supporting member mounted for reciprocating movement and for lateral swinging movement to either side of the machine.

13. In a machine of the character described, a frame, a reciprocating and laterally movable hoe for scraping material rearwardly toward the frame, and a sectional conical hopper extending about the front part of the machine so that the material may 90 be scraped upwardly along the same irrespective of the angle that the line of movement of the hoe makes with the center line of the machine when the hoe is retracted.

14. In a machine of the character described, a frame, a reciprocating and laterally movable hoe and hoe support for scraping material rearwardly toward the frame, and a sectional conical hopper extending about the front part of the machine so that the material may be scraped upwardly 100 along the same irrespective of the angle that the hoe support makes with the center line of the machine when the hoe and support are retracted, said sectional hopper comprising a fixed middle portion at the front of the machine, and removable lateral portions.

In testimony whereof, we hereunto affix our signatures.

FRANK BILLINGS.
ROBERT P. GREENLEAF.
